PIPE FOR SMOKING TOBACCO

Frank M. Ashley, Great Kills, Staten Island,
N. Y., assignor to Lewis Gompers, as trustee

Application August 14, 1937, Serial No. 159,090

10 Claims. (Cl. 131—202)

My invention relates to pipes for smoking tobacco.

The object of my invention is to provide a pipe having means for supporting a filter carried by the mouth-piece of the pipe, in the stem of the pipe in such a manner as to permit the filter to be ejected or dropped from the supporting means without touching the filter in the act of removing the mouth-piece from the stem, or thereafter.

10 A further object is to provide means for supporting a filter made from a short section of a pipe-cleaner of the type in common use comprising a central metal core, in such a manner as to prevent the filter from contacting the wall of the bore formed in the stem of the pipe so that the smoke may come in contact with the surface of the filter on all sides thereof in the act of smoking tobacco.

20 A further object is to provide a filter support that may be adjustable longitudinally relative to the mouth-piece so that the filter supporting means may be made shorter than the length of the bore of a pipe having a long stem, to permit the filter supporting means to be used in both a short or long stem, or bore in the stem of a pipe.

25 A further object is to provide a filter support having means for preventing the filter from closing the adjacent end of the passage formed in the mouth-piece.

30 A further object is to provide a pipe which may be used without the filter, and the passages of which may be cleaned without removing the filter supporting means, by the use of the ordinary pipe-cleaner made for the purpose.

35 Referring to the drawing which forms a part of the specification:

Fig. 1 is a longitudinal sectional view of a pipe having my preferred form of filter support extending from the mouth-piece into the bore formed in the pipe-stem of a long stemmed pipe, with a filter of the character described resting thereon.

40 Fig. 2 is a perspective view of the mouth-piece and filter support such as shown in Fig. 1 and illustrating the adjustable feature of the support relative to the mouth-piece, the dotted lines illustrating it in extended position.

45 Fig. 3 is a cross sectional view taken on line 3—3 of Fig. 1 in which view the dotted circle indicates the outline of the end of a filter carried on the supporting means.

50 Fig. 4 is a longitudinal sectional view of a portion of a pipe having a shorter stem than that shown in Fig. 1 and a support and filter of less length, which support and filter could be used with a long stemmed pipe such as shown in Fig. 1.

55 Fig. 5 is a longitudinal sectional view of a pipe and filter supporting means carried by the mouth-piece and formed as shown in Fig. 6.

60 Fig. 6 is a construction showing one form of

filter support made of thin sheet metal formed to provide a tubular portion which fits over the inner end of the mouth-piece, and which provides two side extending portions adapted to support a filter out of contact with the inner wall of the bore formed in the stem, but may be so spaced as to permit the filter to rest between the side extending portions and on the lower side of the bore of the stem in such a manner as to permit a filter to drop from between the said extending portions when the mouth-piece is removed from the stem.

Fig. 7 is an end view of the construction shown in Fig. 6 taken on line 7—7 thereof.

Fig. 8 is a view of the blank prior to forming the support as illustrated in Fig. 6.

Hereinafter the filter supporting means will be referred to as the support.

20 indicates the bowl of a pipe, 21 the stem, and 22 the mouth-piece.

The pipe is made with a small passage 23 leading from the bowl to an enlarged bore 24, the opposite end of which is closed by the inner end of the mouth-piece.

The mouth-piece is provided with a passage 25 of less diameter than that of the bore.

In Figures 1 to 4 inclusive the filter support is shown in its most simple form and is made of metal wire or other suitable material, preferably of resilient stainless steel, formed as shown in Figure 2, by bending it to provide an upwardly extending semi-circular portion 26, two longitudinally extending side portions 27—27 respectively, two upwardly extending abutment portions 28—28 respectively, and two end portions 29—29 respectively, which extend into apertures 30—30 respectively, formed in the end of the mouth-piece and adjustable longitudinally therein to position the support in a selected position in the bore of the stem.

40 The side portions 27 are positioned to rest in a plane below the openings 23 and 25, and the ends 29 rest on a plane above said openings and out of alignment therewith, thereby permitting a pipe-cleaner to be inserted thru the mouth-piece 45 and passage 23 without obstruction by the support.

The curved end 26 and the abutments 28 serve to prevent the filter 31 from moving end-wise beyond them, thus permitting a filter of short length 50 to be positioned on the support without danger of obstructing the passages 23 or 25, and the filter to be ejected or removed from the support by a jerking motion without touching it when the mouth-piece is removed from the stem or in the 55 act of removing it therefrom.

The filter may be dropped from the support in the act of removing the mouth-piece by first rotating the mouth-piece a one-half revolution prior to or during the removal of the mouth-piece, 60

in the construction illustrated in the first seven figures of the drawing, or by rotating the pipe as a whole prior to removing the mouth-piece, as will be readily understood.

5. In Figures 6, 7, and 8, I have shown a modified form of construction and illustrated a filter support made of sheet metal and formed to provide two thin side portions 27-27 respectively the outer free ends of which are shown as turned in 10 toward each other a limited distance to provide an abutment to limit the movement of the filter, and to permit a space 32 through which a pipe-cleaner may pass in cleaning the passage 28, but if desired these inwardly turned ends may be 15 dispensed with where a short length of filter is used which does not project beyond the free ends of the side portions.

To strengthen the construction of the side portions when made of sheet metal, I may fold the 20 metal on the dotted lines shown in Figure 8, to increase their stiffness.

The side portions in Fig. 6 are formed integral with a cylindrical portion 33 which fits over the inner end of the mouth-piece as illustrated in 25 Figure 5, and is removable therewith from the stem 21.

While I prefer to form the two side portions illustrated in Fig. 2, in joined relation, I may make them as separate parts spaced apart the 30 proper distance to form a filter support, and carried by the mouth-piece, but I prefer to make them as shown in Fig. 2 which prevents them from being accidentally bent apart, as will be readily understood.

35. The constructions above described are easy to make, low in cost, and do not alter the outline of the pipe.

The filters used are inexpensive and serve to provide a dry smoke at a low cost.

40. The pipe may be used without the filter if one is not available, and when used may be removed without soiling the fingers of the user.

Having thus described my invention I claim as new:

45. 1. A pipe comprising a bowl, a stem, and a mouth-piece; a filter support extending from the mouth-piece into the stem and comprising two side portions spaced from each other to support a filter resting between them and extending in 50 permanent parallel relation and formed to provide substantially line supporting surfaces for a filter resting thereon whereby substantially the entire surface of the filter may be exposed to the fluids passing through the stem of the pipe.

55. 2. A pipe comprising a bowl, a stem having a bore formed therein, and a mouth-piece having a passage of less diameter than that of the bore; a filter support carried by the mouth-piece and extending into said bore and formed to provide 60 two narrow side portions on which a filter may rest in spaced relation from the inner wall of the bore, said side portions merging into abutments spaced apart to contact an end of a filter when that end is positioned adjacent the inner end of the mouth-piece whereby smoke may pass between the abutments.

70. 3. A pipe comprising a bowl, a stem having a bore formed therein, a mouth-piece having a passage of less diameter than that of the bore; a filter support carried by the mouth-piece and extending into said bore and having an extended curved surface on which a filter may lie and be supported out of contact with the inner wall of the bore in such a manner as to substantially

expose all sides of the filter resting thereon to smoke passing thru the bore.

4. A pipe comprising a stem and a mouth-piece, a filter support extending from the mouth-piece into the stem adjacent the inner wall thereof comprising two cylindrical rods spaced from each other on which a filter may rest. 5

5. A filter support consisting of a single wire having a fold intermediate the length thereof forming two arms of a bifurcation, each arm having a bend adjacent the fold and additional bends at a distance from the first bend whereby the free end portions of the wire constitute supporting prongs lying in the same plane which plane substantially includes the center point of said fold. 10

6. A filter support consisting of a single wire having a fold intermediate the length thereof forming two arms of a bifurcation, each arm having a bend adjacent the fold and additional bends at a distance from the first bend whereby 20 the free end portions of the wire constitute supporting prongs lying in the same plane which plane substantially includes the center point of said fold, portions of the arms of the wire between the first bends and the last bends being 25 spaced but sufficiently close to readily releasably support a filter thereon.

7. A filter support consisting of a single wire having a fold intermediate the length thereof forming two arms of a bifurcation, each arm 30 having a bend adjacent the fold and additional bends at a distance from the first bend whereby the free end portions of the wire constitute supporting prongs lying in the same plane which plane substantially includes the center point of said fold, the free ends being straight and parallel. 35

8. In combination with a filter support consisting of a single wire having a fold intermediate the length thereof forming two arms of a bifurcation, each arm having a bend adjacent the fold and additional bends at a distance from the first bend whereby 40 the free end portions of the wire constitute supporting prongs lying in the same plane which plane substantially includes the center point of said fold, a mouth-piece having a 45 central bore and bores shorter than the central bore on opposite sides of the central bore adapted to slidably receive the free end portions of the wire.

9. A filter support consisting of a single wire 50 having a fold intermediate the length thereof forming two arms of a bifurcation, each arm having a bend adjacent the fold and additional bends at a distance from the first bend whereby the free end portions of the wire constitute supporting prongs lying in the same plane which plane substantially includes the center point of said fold, the bends adjacent the free end portions being spaced to permit smoke to pass therebetween. 55

10. A filter support consisting of a single wire having a fold intermediate the length thereof forming two arms of a bifurcation, each arm having a bend adjacent the fold and additional bends at a distance from the first bend whereby 60 the free end portions of the wire constitute supporting prongs lying in the same plane which plane substantially includes the center point of said fold, the bends adjacent the free end portions being sufficiently close and sufficiently spaced to 65 act as an abutment and to provide a passageway for smoke. 70
